RAIL FLAW DETECTOR MECHANISM

William E. Mesh, Teaneck, N. J., assignor to
Sperry Products, Inc., Hoboken, N. J., a corpora-
tion of New York

Application July 28, 1948, Serial No. 41,013

5 Claims. (Cl. 175—183)

1

This invention relates to rail flaw detector mechanisms and is particularly designed for application upon the type of detector mechanism employed on the Sperry Rail Flaw Detector Car. This car operates upon the principle of energizing the rail with flux, as, for instance, by passing current through the rail to establish an electromagnetic field surrounding the same, and exploring said field by inductive means to discover any irregularities caused by the presence of fissures or other discontinuities in the rail. The particular problem which presents itself arises from the fact that the speed of the car may vary so that for the same discontinuity in the rail there may be induced a larger or smaller voltage depending upon the speed of the car. Since the voltage thus induced is designed, after amplification, to trip a relay when the output voltage of the amplifier exceeds a predetermined voltage, it will be seen that the tripping point may be reached by a smaller or larger discontinuity if the speed is increased or decreased, respectively.

It is, therefore, the principal object of this invention to provide a method and means which will insure that the tripping output voltage of the amplifier will always represent the same size discontinuity regardless of the varying speed of the detector car.

Further objects and advantages of this invention will become apparent in the following detailed description thereof.

In the accompanying drawings,

Fig. 1 is a side elevation of a portion of a rail fissure detector car having my invention applied thereto.

Fig. 2 is a wiring diagram of one embodiment of this invention.

Figs. 3A, 3B and 3C are a series of interrelated graphs illustrating the principle of this invention.

Fig. 4 is a view similar to a portion of Fig. 2 but showing a modified form of the invention.

Referring to Fig. 1 of the drawing, there are shown the parts of a standard Sperry rail fissure detector car which includes a car body 10 operating along the rails R. Fissure detection is accomplished by energizing the rail with flux, as, for instance, by passing current through each rail from a generator G within the car body supplying current to spaced current brushes 11 and 12 supported upon the current brush carriage 13 which when in lowered or effective position is adapted to ride upon the rail by means such as wheels 15. The current brush carriage 13 is normally held in elevated or ineffective position by means of springs, not shown, and cables 16, but when it is desired to lower said carriage, fluid pressure such as compressed air is supplied to the cylinders 17 to force out pistons 18 which

2

are pivotally connected at 19 to the current brush carriage 13. The current passed through the rail by way of spaced brushes 11 and 12 will establish an electromagnetic field surrounding the rail and this field will be uniform except in the region of flaw, where it will be distorted. Such distortions of the electromagnetic field are detected by a flaw responsive mechanism including housing 20 in which are positioned one or more pairs of opposed induction coils 22. The housing 20 is supported at a constant distance above the rail surface by means of a carriage 24. Said carriage 24 is mounted on current brush carriage 13 by means of loosely fitting bolts 25 and springs 26 to permit said carriage 24, while riding on the rail on means such as wheels 27, to move independently of carriage 13 so that the said carriage 24 may at all times maintain parallelism with the rail surface regardless of irregularities thereof. The coils 22 normally cut the same number of lines of force, but on entering a region of flaw, first one coil and then the other will cut a different number of lines of force to generate a differential E. M. F. which after being suitably amplified by an amplifier A may be caused to actuate a pen P operating on a chart C. At the same time that the pen is actuated, there is actuated also marking means which may take the form of a paint gun 30 mounted on the current brush carriage 13 a sufficient distance behind the flaw responsive members 22 to compensate for the movement of the car and for the lag in operation of the paint gun. The rails are held together by joints which may comprise an angle bar 32, bolts 33, and additional members, all of which constitute the rail joint. This rail joint serves to deflect the current passing through the rails and vary the electromagnetic field surrounding the same. The irregularities of the angle bar will cause the detector coils to pick up a large number of variations not due to discontinuities in the rail. Therefore, a pair of joint cut-out fingers 60 and 60' pivoted at points 61 are provided before and after the detector unit, and designed to be tripped by the angle bar to render ineffective the indicating mechanism for the interval that the detector unit passes over the angle bar, as more fully disclosed in Patent No. 2,069,030 to H. C. Drake granted January 26, 1937.

The output from amplifier A will actuate the pen P against the action of a spring 51 provided the output voltage through relay coil 50 exceeds a predetermined magnitude. As explained in the introduction hereto, a given discontinuity will cause coils 22, for example, to induce an E. M. F. which, after being amplified by amplifier A, yield an output voltage which exceeds the predetermined magnitude necessary to actuate pen P.

However, if the speed of the car is reduced, it will be seen that the same discontinuity will yield an output from the amplifier which is below the predetermined operating magnitude. Conversely, a discontinuity which at one speed of the detector car induces a voltage which, after amplification, is insufficient to actuate the pen P will, if the speed of the car is increased sufficiently, yield an output voltage which will actuate the pen. Since unavoidably the speed of the car varies with different operating conditions such as different rail conditions, and since it is desired that the tripping point or minimum voltage output of the amplifier which will cause actuation of pen P shall always represent the same size discontinuity, means must be provided for compensating for the variations introduced by the variations in speed of the car. Thus, for example, if it is desired to indicate all fissures in excess of 10% area of the head regardless of the speed of the car, then it is seen that means must be provided for preventing a 5% fissure from actuating the pen when the speed of the car is doubled. Similarly, means must be provided for preventing the failure of the pen P to operate at a 15% fissure because the speed of the car has been reduced to half.

The basis of the solution offered by the present invention to the above problem is disclosed in the graphs of Figs. 3A, 3B and 3C. In graph 3A will be seen that in the operating range of the car between 7 and 12 miles per hour the searching unit output voltage which resembles a sine curve will rise approximately 32%. At the same time the rate of increase of the output voltage is in direct ratio, i. e., $5/7$ ths or 71.5%, as shown in graph 3B. It is this latter fact which is utilized to provide the solution of the problem which constitutes this invention.

I provide an amplifier A of a type whose voltage output decreases with increase in the rate of the signal voltage input. Such an amplifier is a low-pass frequency amplifier with gradual cut-off so that the output voltage falls off with increase in the rate of the input signal voltage. Specifically, such an amplifier employs a filter unit 55 comprising capacitor 56 and resistor 57 in parallel. The constants of the filter 55, i. e., the specific values of the capacitor 56 and resistor 57 are so chosen as to give the desired ratio. In this case, it is desired that the output voltage from the amplifier decrease about 32% as the input rate of voltage change varies over the operating range disclosed in Fig. 3B. Thus, while in the operating range of car speed from 7 to 12 miles per hour, the induced signal voltage increases 32% and the rate of the induced signal voltage increases from a rate corresponding to 28 to a rate corresponding to 48, the output voltage of the amplifier in response to such increased rate of signal voltage input should decrease 32%. If graphs 3A and 3C are compared, it will be seen that the graph 3A is at every point in the operating range the same percentage above unity as the amplifier output voltage is below unity. Thus, at every point in the operating range the output voltage of the amplifier compensates for the increased speed to the extent necessary to give a uniform constant output of the amplifier for any given discontinuity in the rail regardless of variation of speed within the operating range.

In a modified form of the invention, a linear amplifier A' may be employed, and the low-pass filter 55 with gradual cut-off may be positioned in advance of the amplifier, as shown in Fig. 4.

Having described my invention, what I claim and desire to secure by Letters Patent is:

1. In a rail flaw detector car, means for energizing the rail with flux, detector means responsive to variations in said flux caused by a defect and adapted to induce a voltage whose magnitude and rate of increase are functions of the speed of the car, and a low-pass filter connected to said detector means and having gradual cut-off for discriminating said induced voltages, whereby the output from said filter diminishes as the rate of increase of the induced voltage increases.

2. In a rail flaw detector car, means for energizing the rail with flux, detector means responsive to variations in said flux caused by a defect and adapted to induce a voltage whose magnitude and rate of increase are functions of the speed of the car, and a low-pass amplifier connected to said detector means and having gradual cut-off for amplifying said induced voltages, whereby the amplifier voltage output diminishes as the rate of increase of the voltage input increases.

3. In a rail flaw detector car, means for energizing the rail with flux, detector means responsive to variations in said flux caused by a defect and adapted to induce a voltage whose magnitude and rate of increase are functions of the speed of the car, and an amplifier connected to said detector means for amplifying said induced voltages, said amplifier having means whereby the amplifier voltage output is constant for any given defect regardless of the speed of the car, said last named means including a low-pass filter with gradual cut-off.

4. In a rail flaw detector car, means for energizing the rail with flux, detector means responsive to variations in said flux caused by a defect and adapted to induce a voltage whose magnitude and rate of increase are functions of the speed of the car, and an amplifier connected to said detector means for amplifying said induced voltages, said amplifier including a low-pass filter with gradual cut-off, the constants of said filter being of such values that the amplifier output voltage diminishes as the rate of increase of the input voltage increases.

5. In a rail flaw detector car, means for energizing the rail with flux, detector means responsive to variations in said flux caused by a defect and adapted to induce a voltage whose magnitude and rate of increase are functions of the speed of the car, and an amplifier connected to said detector means for amplifying said induced voltages, said amplifier including a low-pass filter with gradual cut-off, the constants of said filter being of such values that for any given defect the amplifier output voltage diminishes as the rate of increase of the input voltage increases and to the same degree that the induced voltage increases with increased speed.
